UNITED STATES PATENT OFFICE.

GUSTAVUS A. SCHLECHTER, OF READING, PENNSYLVANIA.

WATCHCASE.

No. 848,131.

Specification of Letters Patent.

Patented March 26, 1907.

Application filed May 16, 1906. Serial No. 317,126.

To all whom it may concern:

Be it known that I, GUSTAVUS A. SCHLECHTER, a citizen of the United States, residing at Reading, in the county of Berks and State 5 of Pennsylvania, have invented certain new and useful Improvements in Watchcases, of which the following is a specification.

This invention relates to improvements in watchcases; and the object of the invention 10 is to provide a watchcase with a suitable opening therein for the purpose of removably securing an emblem, picture, or other device therein.

The invention consists in forming the case 15 with a single central perforation, in the wall of which is provided suitable securing means for said emblem.

In a closed or hunting-case watch either one or both sections of the case may be provided with my invention.

The invention is more fully described in the following specification and clearly illustrated in the accompanying drawing, in which--

25 Figure 1 is a plan view of a watchcase, showing my invention. Fig. 2 is a plan view of the under side thereof. Fig. 3 is a central sectional view taken on line X X of Fig. 1.

The numeral 1 designates a section of a 30 watchcase. In the center of this case I form an opening 2. In the wall of this opening I form, either integral therewith or securely fastened in said case, a retaining-ring 3. This

ring 3 is formed with a bead 4 on the exposed side of the case and extends some distance 35 into the case. On its inner edge I form a plurality of flexible fingers 5.

An emblem or like device may be inserted in the retaining-ring from the inside of the case, and the fingers 5 are then bent to press 40 against it, and thus retain it in position. It is evident that this emblem may be removed and replaced at will.

Having thus fully described my invention, what I claim, and desire to secure by Letters 45 Patent, is—

1. A watchcase-lid having a comparatively large, central, circular opening, a retaining-ring secured in said opening and means for removably retaining an emblem or like device in said ring.

2. A watchcase-lid formed with a comparatively large, central, circular opening, a retaining-ring secured in said opening, a bead formed on the exposed end of said ring, and a 55 plurality of flexible retaining-fingers formed on the inner edge of said ring adapted to removably retain an emblem or like device.

In testimony whereof I have signed my name to this specification in the presence of 60 two subscribing witnesses.

GUSTAVUS A. SCHLECHTER.
